(57) **CLAIM**

The ornamental design for an injector body, as shown and described.

DESCRIPTION

FIG. 1 is a top perspective view of a injector body;

FIG. 2 is a top plan view thereof;

FIG. 3 is a right elevational view thereof, the left elevational view being a mirror image of the right elevational view;

FIG. 4 is a rear elevational view thereof;

FIG. 5 is a front elevational view thereof; and,

FIG. 6 is a bottom plan view thereof.

The elements shown in broken lines in FIG. 1 depict environmental structures and form no part of the claimed design.

The broken lines shown in FIGS. 4 and 5 represent the bounds of the claimed design and form no part of the claimed design.
